UNITED STATES PATENT OFFICE.

HAROLD W. NICHOLS, OF MAPLEWOOD, NEW JERSEY, ASSIGNOR TO WESTERN ELECTRIC COMPANY, INCORPORATED, OF NEW YORK, N. Y., A CORPORATION OF NEW YORK.

SECRET CARRIER WAVE SIGNALING SYSTEM.

Application filed November 19, 1920. Serial No. 425,075.

To all whom it may concern:

Be it known that I, HAROLD W. NICHOLS, a citizen of the United States, residing at Maplewood, in the county of Essex, State of New Jersey, have invented certain new and useful Improvements in Secret Carrier Wave Signaling Systems, of which the following is a full, clear, concise, and exact description.

10 This invention relates to a signaling system in which signals are transmitted by the agency of a high frequency wave modulated in accordance with signals, and more particularly to a means for rendering the operation of such a system secret.

15 Its object is to provide a system of wireless or wire communication whereby secret communication between stations may be had to the end that stations, other than the one 20 designed to receive, may not receive intelligible signals.

25 The principle of the invention resides in the transmission of an auxiliary wave having a particular frequency together with the modulated carrier wave. An attempt to detect the received energy by any ordinary means results in the presence, in the output circuit of the detecting means, of a wave having audible frequency and containing the 30 elements of the signal wave but sufficiently distorted from the desired form as to be incapable of intelligent reception.

35 The expression "secret signaling" implies the provision of a means for normal detection by the desired station and the invention accordingly includes as an additional feature circuit means at a receiving station for rendering the auxiliary transmitted wave ineffective in interfering with the normally 40 transmitted and detected signal wave.

45 More specifically the method of secret signaling according to the present invention involves the following steps: An inaudible frequency carrier wave is modulated in accordance with an audible frequency signal wave. The modulation is accomplished by some means, preferably a balanced type modulator, which produces a pure modulated wave, the unmodulated component, or 50 such component and one side band, being suppressed. A pure modulated wave may, for purposes of defining applicant's invention, be described as any modulated carrier wave from which the unmodulated carrier 55 component has been substantially eliminated.

The output wave of the modulator is transmitted to the distant station together with an auxiliary wave. The frequency of the auxiliary wave is so selected as to differ from that of the unmodulated component by an 60 audible frequency and means are provided to insure that intermodulation does not occur at the transmitter between this wave and the remaining transmitted components. At the receiving station, the received waves 65 are detected. The product of the detecting operation is a plurality of separable waves of audible and inaudible frequencies, included in the former being the distorted signal wave above described. The audible 70 frequency waves are passed through a band filter which suppresses the waves having frequencies above and below the frequencies corresponding to the difference between the auxiliary frequency and the lower side band 75 frequencies of the pure modulated wave transmitted. The resulting component is subjected to a second detecting operation in which it is combined with a wave from a local source having a frequency equal to 80 the difference between the frequencies of the unmodulated component and auxiliary waves at the transmitting station. This operation results in the production of a low frequency wave similar in all respects to 85 the signal wave and which may be separated from the remaining components resulting from the operation and caused to energize a telephone receiver to give an acoustic 90 signal.

95 The principle of the invention has been briefly described above. Before entering on a more detailed disclosure of the invention, especially as embodied in a specific form, attention will be given to the mode of operation of certain elements which recur in several places in the system in slightly different forms. Included among these elements are the balanced type modulator, the function of 100 which has been briefly described, and the more common detector or single tube modulator.

105 In this connection reference is made to British Patent No. 102,503, which contains a detailed account of the operation of a balanced modulator, as well as a disclosure of the basic theory of the detecting or modulating operation. According to the mathematical analysis there set forth of the 110 action of a modulator, and it is equally true

as applied to any two of the input waves of a detector, the complex wave resulting from the combination of two input waves may be resolved into component waves two of which have respectively their sum and difference frequencies. Expressed in another way, the result of the modulation of a high frequency carrier wave according to a low frequency signal is a band of three high frequency waves comprising the carrier, or unmodulated component, and the upper and lower side bands. The double frequency harmonics of each of the input waves are also obtained but these are, in general, widely different in frequency from the components to be utilized and are therefore readily separable therefrom.

The combination of two modulator tubes in a balanced modulator system according to the arrangement of the patent serves to suppress the unmodulated carrier component leaving only the two high frequency components representing the side bands.

The detecting operation of a tube having a characteristic similar to that of a modulator tube, yields a wave made up of components having frequencies of the sum and difference of the input frequencies. If an unmodulated carrier wave component is transmitted, or if the unmodulated carrier component is suppressed at the transmitter and reinserted in the receiving conductor, as in the so called homodyne system of the British patent, the combination in the detector of the component frequencies according to the principles above enunciated results in a current of signal frequency which can be separated from currents of other frequencies and used to actuate a telephone receiver.

For a more detailed disclosure of the invention, as embodied in a practical form, reference is made to the following description taken in connection with the accompanying drawing in which Fig. 1 shows in a diagrammatical form an arrangement of the transmitting circuits of the invention; Fig. 2 shows an arrangement of the receiving circuits of the invention and Fig. 3 shows an alternative form of a portion of the circuits of Fig. 1.

Referring to Fig. 1, "M" is a modulator of the balanced type which is fully disclosed in the British Patent No. 102,503 above mentioned and will not be further described here, except to point out that the high frequency unmodulated component is impressed on the common input circuit by means of source C, and that the low frequency signal component is impressed on the input circuits of both modulator units by means of low frequency source S which may be a microphone, as shown, although other means may be used depending on the particular use to be made of the system.

Although a particular type of modulator has been shown, other types which have in common with it the distinguishing characteristic that the unmodulated component is suppressed, may be used.

The frequencies of the currents from the sources C and S will be indicated in the description that follows by the same reference characters but using small letters instead of capitals. There will exist in the secondary of transformer B currents having the side band frequencies $c-s$ and $c+s$ as has been described, the unmodulated component of carrier frequency c having been suppressed.

According to the present invention currents of the side band frequencies are transmitted together with currents having an auxiliary frequency k . This is accomplished by means of the hybrid coil or balanced network D conjugately connecting the auxiliary frequency source K with the modulator output, by means of which the side band and auxiliary frequency components are independently transmitted without intermodulation. The prevention of intermodulation is due both to the fact that the conjugate points have no difference of potential for currents of frequency k which are therefore not impressed on modulator M and to the non-modulating characteristic of amplifier A. The artificial network R functions in the usual manner to perfect a balance in the two portions of the divided network. The currents of frequencies $c-s$, $c+s$ and k are independently transmitted by means of transformer F to transmitting conductor E which is here shown as a radio antenna although it can equally well be a terminus of a transmission line.

By means of the arrangement shown, an interceptor is unable, by any ordinary means, to intelligibly detect the received signal waves if the frequency k is properly chosen so that frequency $k-c$ is within audible limits. That this is true is at once made evident by writing down the combinations resulting from intermodulation of the three frequencies $c-s$, $c+s$ and k in the detecting device according to the principles that have been enunciated. For instance, the sum and difference frequencies $2c$, $2s$, $k+c+s$, $k+c-s$, $k-c-s$ and $k-c+s$ are obtained as well as additional, inaudible, frequencies. The component having frequency $2c$ is audible and, taken alone, would be intelligible as speech although having a different pitch from the transmitted speech. However, if frequency $k-c$ is within audible limits, the component $k-c-s$ will be within the audible range and of a character to effectually mask the speech frequency, inasmuch as this band of frequencies will correspond, depending upon the particular

value of $k-c$, to a more or less complete inversion of the speech frequency components of the speech band. Since, in any process of detection, these combination frequencies would be found in the output of the detecting device, the masking or interfering effect cannot be avoided by any simple detecting means involving the combination of the received waves with the 10 waves from a local source. If, however, frequency $k-c$ is given a value sufficiently high, although within audible limits, it is possible by means of a receiving system constructed according to the present invention to receive intelligible signals.

Referring now to Fig. 2, there is shown a circuit at a receiving station which enables a person familiar with the principles of the invention to receive intelligible signals. The three waves $c-s$, $c+s$ and k which are transmitted from transmitting conductor E are received by receiving conductor G, here shown as an antenna, and detected by detecting means D_1 . The product of the detecting operation, as has just been pointed out includes components of current having the sum and difference frequencies $k-c+s$, $k-c-s$ and $2s$, these being the only components having audible 20 frequencies. The currents of frequencies $k-c+s$ are transmitted by band filter BF which suppresses frequencies above and below the limits of the frequency band determined by this expression.

Currents of this frequency are combined with currents of frequency $k-c$ from source K-C by means of detector D_2 , the currents being impressed on its input circuit by means of transformers J and R₁. The output current of this detector includes components having audible frequencies $k-c+s$, $k-c$ and s . If $k-c$ has a value corresponding substantially to the upper limit of speech frequencies, the component $k-c+s$ can be 30 easily separated from the component frequency s . Five or six thousand cycles has been considered a good value for this difference frequency and if given this value, the component $k-c$ may also be separated from the speech frequency component, although the constant tone resulting from this component would not render the speech unintelligible.

The speech frequency components are 40 separated from these other components by means of low pass filter LF and are transmitted to the indicating means which may be a telephone receiver. It may be desirable to amplify the voice frequency currents and amplifier A₁ and transformer O are accordingly shown interposed in circuit between the filter and indicating device.

It is apparent from the above that the 50 efficient operation of the system depends largely on keeping the frequency $k-c$ at the

receiver equal to the difference of frequencies k and c at the transmitter. Since this difference depends on the frequencies of two sources, it is subject to greater casual variation than is true of source K-C. By the 70 arrangement of Fig. 3, the frequencies c and k may be so related that the difference therebetween may be more nearly constant than by the means shown in Fig. 1 and substantially as constant as if the current of this 75 difference frequency were the product of a single source.

The circuits of Fig. 3 may be applied to the system of Fig. 1. A portion of the output of high frequency c is combined with a current from source T in modulating device M₁. The resulting unmodulated component and lower side band are suppressed by means of high pass filter HF which transmits currents having a frequency measured by 80 the sum of the frequencies t and c . For a properly selected value of t , which, for example, may be given a value $k-c$, the difference frequency will be the same as the frequency k from the source K of Fig. 1. If 85 the frequency c varies this derived frequency will no longer equal k but it is readily apparent that it will increase with frequency c and that the difference between this frequency and that of c will be constant. Accordingly, any fluctuation in the difference frequency $k-c$ will be due the fluctuation in the source T alone and a more constant effect is secured than by the arrangement 90 disclosed in Fig. 1.

Although the system of the invention has been disclosed in connection with a radio transmission system, the theory of operation is not inconsistent with its use in a wire transmission system and the invention is not to be 100 understood as limited in scope by such disclosure, but only by the scope of the appended claims.

What is claimed is:

1. The method of secret carrier wave signaling comprising, at the transmitting station, the steps of modulating a high frequency carrier wave in accordance with a signal wave, independently transmitting the modulated carrier wave and an auxiliary 110 wave differing in frequency from the carrier frequency by an audible amount, and at the receiving station, the steps of detecting said transmitted wave, causing intermodulation between the product of said detecting 115 operation and a wave having a frequency equal to the difference between the carrier and auxiliary wave frequencies, and separating the signal frequency component from the resulting product.

2. A method of secret carrier wave signaling comprising the steps of modulating a high frequency carrier wave according to a signal, suppressing the unmodulated component, transmitting the remaining compo- 120 125 130

nents and transmitting therewith, but independently thereof, an auxiliary frequency wave having a frequency differing from the frequency of said carrier wave by an audible amount.

3. The method of carrier wave signaling which comprises the steps of generating a carrier wave, modulating said wave in accordance with control impulses, suppressing a portion of said modulated wave including substantially all of the unmodulated carrier component, radiating the resultant wave, and radiating simultaneously therewith but independently thereof an auxiliary wave differing in frequency from the carrier frequency by an audible amount.

4. The method of secret carrier wave signaling comprising, at the transmitting station the steps of modulating a carrier wave in accordance with a band of frequencies, suppressing the unmodulated carrier component and independently transmitting at least one of the modulated carrier side bands and an auxiliary wave differing in frequency from the carrier frequency by an audible amount, and at the receiving station the steps of detecting the said transmitted waves, causing intermodulation between the product of said detecting operation and a wave having a frequency equal to the difference between the carrier and auxiliary frequencies, and separating the signal frequency component from the resulting product.

5. The method of secret carrier wave signaling which consists in modulating a high frequency carrier wave in accordance with a wave of a band of frequencies, suppressing the unmodulated carrier component, independently transmitting at least one of the modulated carrier side band components and an auxiliary wave differing in frequency from the unmodulated carrier component by an audible amount, receiving and detecting said waves, filtering out the lower side band component of the wave resulting from the combination in the detecting device of the auxiliary frequency wave and the lower transmitted side band, modulating therewith a wave having a frequency equal to the difference between the auxiliary and carrier frequencies, filtering out the signal frequency component of the modulating operation and causing said signal frequency component to actuate an indicating means.

6. The method of secret carrier telephony which consists in modulating a carrier wave in accordance with a signal, suppressing the unmodulated carrier component, independently transmitting at least a portion of the resultant wave and an auxiliary wave differing in frequency from the unmodulated component by substantially the upper limit of speech frequency, receiving and detecting said waves, filtering out the lower side band component of the wave resulting from the

combination in the detecting device of the auxiliary frequency wave and the lower transmitted side band, modulating therewith a wave having a frequency equal to the difference between the auxiliary and carrier frequencies, filtering out the signaling frequency component of the modulating operation and causing said signal frequency component to actuate an indicating means.

7. The method of radio telephony of the modulated carrier current type which comprises the steps of modulating a carrier wave in accordance with a signal wave, suppressing the unmodulated carrier component, independently radiating the resultant wave and an auxiliary wave having a frequency differing from the unmodulated component by substantially the upper limit of speech frequency, receiving and detecting said waves, filtering out the lower side band component of the wave resulting from the combination in the detecting device of the auxiliary frequency wave and the lower transmitted side band, modulating therewith a wave having a frequency equal to the difference between the auxiliary and the carrier frequencies, filtering out the signal frequency component of the modulating operation and causing said signal frequency component to actuate an indicating means.

8. A secret carrier wave signaling system comprising in combination means for generating a carrier wave, means for modulating said wave in accordance with a signal, means for suppressing the unmodulated carrier component, an auxiliary source adjusted to generate a wave having a frequency differing from the carrier frequency by an audible amount, means for independently transmitting the resultant modulated wave and said auxiliary wave, a receiving conductor, a detecting device, a local source adjusted to generate a wave having a frequency equal to the difference between the frequencies of said carrier and auxiliary waves, a modulating means for combining with the output wave of said detecting device the wave from said local source, and means for separating the signal frequency component from the output wave of said modulating means.

9. A secret carrier wave radio telephone system comprising in combination a duplex balanced type modulator adjusted to produce a pure modulated wave, a source of carrier waves and a source of signal waves associated with said modulator, an auxiliary source adjusted to generate a wave having a frequency differing from the carrier frequency by substantially the upper limit of speech, means for independently radiating said pure modulated wave and said auxiliary wave, a receiving conductor, a detector, a band filter adapted to transmit the lower side band component resulting from the combination in the detector of the auxiliary

- waves and the lower side band of the pure modulated wave, a local source adjusted to generate a wave having a frequency equal to the difference between the frequencies of said carrier and auxiliary waves, a modulating means for combining said component with a wave having a frequency equal to the difference between frequencies of said carrier and auxiliary waves, a low pass filter for transmitting only the speech frequency component of the modulator output wave, and an indicating means.
10. The method specified in claim 2 in which the auxiliary wave is derived from the carrier wave by a method comprising the steps of intermodulating a portion of the output of the carrier source with a wave having a frequency which differs from the desired auxiliary frequency by substantially 15 the mean carrier frequency, and suppressing all but the desired auxiliary frequency component resulting from said modulation.
20. 11. A method of secret carrier wave signaling which comprises the steps of generating a carrier wave, modulating said wave in accordance with speech, suppressing the unmodulated carrier wave, transmitting at least one of the remaining side bands, and transmitting therewith, but independently thereof, an auxiliary frequency wave having a frequency differing from the frequency of said carrier wave by an audible amount.
12. A secret carrier wave signaling system comprising means for generating a carrier wave, means for modulating said wave in accordance with a signal wave, means for suppressing the unmodulated carrier component, an auxiliary wave source adjusted to generate a wave differing in frequency from the carrier wave by an audible amount, and means for independently transmitting at least a portion of the resultant modulated carrier wave and said auxiliary wave.

In witness whereof I hereunto subscribe my name this 11th day of November, A. D., 1920.

HAROLD W. NICHOLS.
